EXTRUSION HEAD FOR CAULKING GUN

Clifford B. Archer, 5563 E. Dakota,
Fresno, Calif. 93727

Filed Jan. 23, 1975, Ser. No. 543,254

Term of patent 7 years

Int. Cl. D8—05

U.S. Cl. D8—14.1

FIG. 1.

FIG. 2.

FIG. 3.

FIG. 4.

FIG. 5.

FIG. 6.

FIG. 7.

FIG. 8.

FIG. 1 is a side elevation of an extrusion head for caulking gun showing my new design, with a caulking gun shown in broken lines for illustrative purposes.

FIG. 2 is a perspective view thereof.

FIG. 3 is a top plan view thereof.

FIG. 4 is a bottom view thereof.

FIG. 5 is a side view thereof, similar to FIG. 1, but on an enlarged scale.

FIG. 6 is a side view thereof illustrating the opposite side thereof opposite the side shown in FIG. 5.

FIG. 7 is an end view thereof.

FIG. 8 is an end view thereof, illustrating the end thereof opposite the end shown in FIG. 7.

I claim:

The ornamental design for an extrusion head for caulking gun, as shown and described.
